INVENTOR,

UNITED STATES PATENT OFFICE.

EUGENE T. TURNER, OF NEW YORK, N. Y.

MUSIC ROLL OR SPOOL AND FLANGE THEREFOR.

1,109,716.

Specification of Letters Patent.

Patented Sept. 8, 1914.

Application filed February 26, 1913. Serial No. 750,822.

To all whom it may concern:

Be it known that I, EUGENE T. TURNER, a citizen of the United States, residing in the city and State of New York, have invented new and useful Improvements in Music Rolls or Spools and Flanges Therefor, of which the following is a specification.

This invention aims to provide certain improvements in rolls or spools such as are used for carrying perforated music sheets for controlling the operation of pianos or other musical instruments; the invention being applicable also to spools used for various other purposes. An important feature of advantage is the making of the end piece or head or "flange," as it is commonly called, of the spool or roll of a single piece of sheet metal stamped into shape whereby these end pieces can be made very rapidly and cheaply.

Various other points of advantage are referred to in detail hereinafter.

The accompanying drawings illustrate an embodiment of the invention.

Figure 1 is a perspective view of the music roll. Fig. 2 is a longitudinal section of the same.

Referring now to the embodiment of the invention illustrated, the body A is a tube of fiber board or similar stiff material carrying the two end pieces B and C. Each of the end pieces is provided with a flange D and a tubular portion E located on the outer side of the flange and embracing the end of the body A with a close fit so that the friction tends to hold it stationary on the body. To prevent detachment of the end piece from the body tongues F are bent inward from the tubular portion E through openings in the body A. The tongues thus formed are located outside of the inner face of the flange D so as to offer no obstruction to the paper fitting closely into the corner G. That is to say, the body A is smooth and unobstructed and extends clear up to the inner face of the flange D. The tubular portion E has a recessed head H for engagement with the end of the supporting or driving shaft. The end piece B has the recessed head H formed with a slot J at its inner end for engagement with the end of a driving shaft K which fits in the circular socket H and has a polygonal end L entering the slot J and serving thereby to turn the roll from the shaft. The socket H

of the opposite end piece C may be a plain circular socket without a slot since it is intended to be merely supported upon the supporting shaft M. The shafts K and M are mounted in the roll-carrying frame in the usual way, the shaft M being pressed toward the shaft K by a light spring which permits it to be thrust back sufficiently to insert the roll and which then presses the two ends of the roll toward each other.

There is considerable expansion and contraction of the paper in ordinary music sheets caused by varying degrees of temperature and humidity in the atmosphere. The flanges should bear against the edge of the paper and one or both of them may be made adjustable to accommodate the varying widths. In the example illustrated the supporting end piece C is made capable of substantial adjustment by reason of the tongues F being located in slots N which are considerably elongated so that the end piece may be shifted a considerable distance outward or inward, but may not be detached from the body. At the opposite end the tongues F fit in slots O of the body which are made as short as is practical. The openings N and O are made in the body of the roll before the end pieces are applied and the latter are then placed on the ends of the body and the tongues F bent inward to the positions indicated. The edge is turned over as at P to stiffen the flange and at the same time to provide a rounded edge of considerable width which will facilitate the free running of the paper off and on the roll.

End pieces of the character described can be made and sold for about half the cost of the metal end pieces now in common use, the latter generally being made in four pieces separately formed and then fastened together; whereas the end piece of the present invention is made of a single piece of metal and has certain advantages in convenience of attachment and in the providing of an absolutely unobstructed body A from end to end between the flanges.

Though I have described with great particularity of detail certain specific embodiments of the invention, yet it is not to be understood therefrom that the invention is restricted to the particular embodiments disclosed. Various modifications in detail and in the arrangement and combination of the parts may be made by those skilled in

the art without departure from the invention.

What I claim is—

1. A music roll or the like comprising a body and an end piece having a flange and having a tubular portion engaging a portion of said body, said tubular portion having a tongue extending into an axially elongated slot in said body so as to fasten it 10 adjustably thereto, said slot being closed to prevent separation of said end portion from said body.
2. A music roll or the like comprising a hollow body A of fiber board and an end piece having a flange D and a tubular portion E, said tubular portion located on the outer side of the flange and engaging the end of the body and having a socket H extending into the end of the body, said 20 flange, tubular portion and socket being formed integrally of a single piece of stamped sheet metal.
3. An end piece for music rolls and the like comprising a tubular portion adapted 25 to embrace the end of a roll body with a close fit, and a transverse circular flange extending outward from the inside edge of said tubular portion, said tubular portion

having a recessed head extending into said tubular portion and adapted to receive the 30 end of a supporting or driving shaft.

4. An end piece for music rolls and the like comprising a tubular portion adapted to fit over the end of a roll body, and a transverse circular flange extending outward from the inside edge of said tubular portion, said tubular portion having a recessed head at its outer end adapted to receive the end of a supporting or driving shaft, said end piece being made of a single 40 piece of sheet metal bent to shape.

5. An end piece for music rolls and the like comprising a tubular portion E adapted to fit over the end of a roll body, a flange D extending outward from the inside edge 45 of said tubular portion, and a socket H formed within the outside edge of said tubular portion.

In witness whereof, I have hereunto signed my name in the presence of two sub- 50 scribing witnesses.

EUGENE T. TURNEY.
